Burnham C. Stickney.

UNITED STATES PATENT OFFICE.

BURNHAM C. STICKNEY, OF ELIZABETH, NEW JERSEY, ASSIGNOR TO
UNDERWOOD TYPEWRITER COMPANY, OF NEW YORK, N. Y., A COR-
PORATION OF NEW JERSEY.

TYPE-WRITING MACHINE.

No. 811,182.

Specification of Letters Patent.

Patented Jan. 30, 1906.

Application filed December 18, 1902. Serial No. 135,361.

To all whom it may concern:

Be it known that I, BURNHAM C. STICKNEY, a citizen of the United States, and a resident of the city of Elizabeth, county of Union, 5 and State of New Jersey, have invented certain new and useful Improvements in Type-Writing Machines, of which the following is a specification.

This invention relates primarily to type-writing machines in which radially-disposed type-bars are arranged about a common printing-point and move one at a time to the printing position. These type-bars, especially in "front-strike" machines, are often 15 closely arranged, so that in rapid operation there is liability of clashing, due largely to the fact that the type-bars are apt to rebound from the basket or cushion upon returning to normal position, thus getting into the path 20 of a subsequently-operated type-bar.

The principal object of my invention, therefore, is to minimize the liability of the type-bars to rebound in this manner.

In the drawings forming part of this specification, and in which like signs denote like parts, Figure 1 is a sectional elevation of a type-bar, type-basket, and platen of an under-strike machine, and by turning the figure quarter-way around it will be seen that it 25 represents like parts in a front-strike machine, in which the type-bars lie horizontally and below the plane of the printing-point. Fig. 2 is a plan of the type-basket or ring seen at Fig. 1, the type-bars being indicated in 30 cross-section. Fig. 3 shows a modification of the basket seen at Fig. 1.

Referring to Figs. 1 and 2, a radial series of type-bars 1, carrying types 2, which strike against a platen 3, is supported by hangers 4 upon a ring, segment, or plate 5 and operated 40 by means of pull-rods 6 or otherwise and usually provided with returning-springs. The type-bars normally rest in contact at their type ends with a flexible ring or segment consisting, preferably, of an annulus or segment 45 of lead or other yielding inelastic metal or substance 7, which may be faced with a softer inelastic substance 8. The latter may consist of a strip such as sometimes used for belt-lacing, some kinds of which are commonly 50 soft, tough, and inelastic, and the strip may be wound around the lead, so as to form a com-

plete casing therefor, as illustrated. The device may be supported in any suitable way, preferably upon inturned fingers 9, formed 55 at the lower edge of a thin stiff sheet-metal ring or band 10, the latter being hung upon rods 11, attached to the top plate 5 or otherwise supported. In front-strike machines the member 10 may be in the form of a segment and in some cases may be omitted.

The facing or swathing 8 prevents the soft-metal ring 7 from being cut by the type-bars and also minimizes the noise of the impacts. The bar 7 being flexible yields more or less at 65 the impacts of the type-bars, and owing to this yielding movement some of the adjacent and opposite type-bars are jarred, thereby taking up much of the force of the blow and minimizing the reaction of the bar 7, so that 70 it does not tend to throw the type-bar back with force, the tendency of the same to rebound being lessened, while owing to the inelastic character of the lead or other metal 75 7 the force of the original blow of the type-bar is still further absorbed, particularly since the bar 7 is faced with a soft inelastic material, so that the bar upon striking the basket may possibly drive slightly past its normal position, but will not rebound to the extent of 80 causing it to clash with a subsequently-operated type-bar. This enables the operation of the machine at high speed without danger 85 from this source.

The curved frame or ring 10 is more substantial than the lead and protects the latter from injury. It also prevents undue displacement of the lead ring or segment. Preferably a narrow space is left at 12 between the ring or segment 10 and the inner member, so 90 as to allow slight freedom of movement of the latter. During such movement there may be more or less friction between the sheathed lead member and the fingers or shelves 9, whereon it is supported, thereby further tending 95 to absorb the force of the type-bar blows.

At Fig. 3 the lead ring or segment 7 is shown bare except for a facing 13 next to the type-bars, consisting of inelastic belt-lacing or of any cushioning material supported in 100 any suitable manner.

Variations may be resorted to within the scope of my present improvements and portions thereof may be used without others.

Having thus described my invention, I claim—

1. In a type-writing machine, the combination with a type-bar of a movable inelastic metallic member forming a rest therefor.
2. In a type-writing machine, the combination with a type-bar of a movable lead rest therefor.
3. In a type-writing machine, the combination with a series of type-bars of a movable ring of lead forming a rest therefor.
4. In a type-writing machine, the combination with a series of type-bars of an inelastic metal rest therefor provided with a facing of fibrous material.
5. In a type-writing machine, the combination with a series of type-bars of a rest therefor consisting of inelastic metal faced with leather.
6. In a type-writing machine, the combination with a series of type-bars of a rest therefor consisting of inelastic metal faced with tough, pliant, inelastic material.
7. In a type-writing machine, the combination with a type-bar of a rest therefor consisting of a body of inelastic metal and a facing of tougher pliant inelastic material.
8. In a type-writing machine, the combination with a series of radially-disposed type-bars of a curved bar of inelastic material forming a rest for said type-bars and faced by a strip of tougher, pliant material.
9. In a type-writing machine, the combination with a type-bar of a movable inelastic metallic member forming a rest therefor and having a facing of tough, pliant material.
10. In a type-writing machine, the combination with a type-bar of a movable inelastic metallic member forming a rest therefor and having a facing of tough, inelastic, pliant material.
11. In a type-writing machine, the combination with a series of type-bars of a bar of inelastic metal faced with inelastic belt-lacing and forming a rest for said type-bars.
12. In a type-writing machine, the combination with a series of type-bars of a curved bar of lead having a facing of yielding fibrous material and forming a rest for said type-bars.
13. In a type-writing machine, the combination with a series of type-bars of a bar of lead faced with inelastic belt-lacing and forming a rest for said type-bars.
14. In a type-writing machine, the combination with a series of type-bars of a rest therefor comprising portions of lead and fibrous material.
15. In a type-writing machine, the combination with a type-bar of a rest therefor consisting of lead faced with tougher pliant material.
16. In a type-writing machine, the combination with a type-bar of a movable rest therefor consisting of lead faced with tough material.
17. In a type-writing machine, the combination with a series of type-bars of a curved movable lead bar faced with tough material and forming a rest for said type-bars.
18. In a type-writing machine, the combination with a series of type-bars of a movable lead bar faced with tough, pliant, fibrous material and forming a rest for said type-bars.
19. In a type-writing machine, the combination with a series of type-bars of a ring of lead having a facing of inelastic belt-lacing and forming a rest for said type-bars.
20. In a type-writing machine, the combination with a series of type-bars of a ring of lead faced with tough, wear-resisting material, and forming a rest for said type-bars.
21. In a type-writing machine, the combination with a series of type-bars of a movable ring of lead faced with tough, pliant, wear-resisting material and forming a rest for said type-bars.
22. In a type-writing machine, the combination with a series of type-bars of a rest therefor consisting of inelastic metal confined within a casing of inelastic pliant material.
23. In a type-writing machine, the combination with a series of type-bars of a rest therefor consisting of inelastic metal incased in inelastic leather.
24. In a type-writing machine, the combination with a series of radially-disposed type-bars of a curved bar of pliant, inelastic material, overwound with a strip of tougher pliant material, and forming a rest for said type-bars.
25. In a type-writing machine, the combination with a series of type-bars of a bar of inelastic metal overwound with inelastic belt-lacing and forming a rest for said type-bars.
26. In a type-writing machine, the combination with a series of type-bars of a curved bar of lead overwound with tough material and forming a rest for said type-bars.
27. In a type-writing machine, the combination with a series of type-bars of a curved bar of lead overwound with inelastic belt-lacing.
28. In a type-writing machine, a type-rest consisting of lead incased in inelastic flexible material.
29. In a type-writing machine, a movable curved rest for type-bars, consisting of lead incased in pliant tough material.
30. In a type-writing machine, a movable type-rest consisting of a ring of lead inclosed in a casing of tough pliant material.
31. In a type-writing machine, a type-rest consisting of a ring of lead overwound with inelastic belt-lacing.
32. In a type-writing machine, the combination with a series of type-bars of a rest therefor consisting of inelastic metal having a backing of stiff metal, the latter being fixed, and the inelastic metal being capable of a limited movement when struck by the type-bars.

33. In a type-writing machine, the combination with a type-rest consisting of inelastic metal and capable of limited movement under the impact of the type-bars, of a fixed 5 rest for said movable rest.
34. In a type-writing machine, the combination of a series of type-bars, a curved pliant movable inelastic bar forming a rest therefor, and a fixed backing of stiffer metal.
- 10 35. In a type-writing machine, the combination of a series of type-bars, a movable lead rest therefor, and a fixed backing for the lead.
- 15 36. In a type-writing machine, the combination with a series of type-bars of a movable lead ring forming a rest therefor, and a fixed ring of stiffer metal inclosing said lead ring.
- 20 37. In a type-writing machine, the combination with a series of type-bars of a rest therefor consisting of inelastic pliant metal faced with tough, pliant material and having a backing of stiff metal.
- 25 38. In a type-writing machine, the combination of a series of type-bars, a curved pliant inelastic metal bar forming a rest therefor 25 and provided with a facing of tough pliant material, and a fixed bar forming a backing for said pliant bar.
39. In a type-writing machine, the combination of a series of type-bars, a lead rest 30 therefor faced with tougher pliant material, and a stiff backing for said rest.
40. In a type-writing machine, a type-bar rest consisting of flexible material housing a metal strip which is inelastic. 35
41. In a type-writer, in combination with the ends of the type-bars that carry the printing characters, a yielding non-resilient pad constructed of thin flexible metal yieldingly supported and arresting the type-bars without causing them to rebound.
42. A type-writer pad constructed of thin, flexible, but non-resilient, metal, yieldingly supported.
